UNITED STATES PATENT OFFICE

CHARLES H. REYNOLDS, OF EVANSTON, ILLINOIS, ASSIGNOR TO THE REYNOLDS-SCHIER CO., INC., OF CHICAGO, ILLINOIS, A CORPORATION OF ILLINOIS

DESIGN FOR A HECTOGRAPH MACHINE

Application filed June 6, 1932. Serial No. 43,990. Term of patent 3½ years.

To all whom it may concern:

Be it known that I, CHARLES H. REYNOLDS, a citizen of the United States, residing at Evanston, in the county of Cook and State of Illinois, have invented a new, original, and ornamental Design for Hectograph Machine, of which the following is a specification, reference being had to the accom-

panying drawing, forming part thereof.

The figure is a perspective view of a hectograph machine showing my new design.

I claim:

The ornamental design for a hectograph machine as shown.

CHARLES H. REYNOLDS.
